US0D1104196S

(12) **United States Design Patent** (10) **Patent No.:** **US D1,104,196 S**
(45) **Date of Patent:** **** Dec. 2, 2025**

(54) **ADJUSTABLE BACK PRESSURE DEVICE
FOR FIREARM SUPPRESSORS**

(71) Applicant: **Everett A. Williams**, Midvale, UT (US)

(72) Inventor: **Everett A. Williams**, Midvale, UT (US)

(73) Assignee: **Sound Moderation Technologies,
LLC**, Raleigh, NC (US)

(**) Term: **15 Years**

(21) Appl. No.: **29/925,304**

(22) Filed: **Jan. 23, 2024**

(51) LOC (15) Cl. **22-01**

(52) U.S. Cl.

USPC **D22/108**

(57) **CLAIM**

The ornamental design for an adjustable back pressure device for firearm suppressors as shown and described.

DESCRIPTION

FIG. 1 is a front, top, and right side perspective view of an adjustable back pressure device for firearm suppressors showing my new design.

FIG. 2 is a back, bottom and left side perspective view thereof.

FIG. 3 is a top view thereof.

FIG. 4 is a bottom view thereof.

FIG. 5 is a right side view thereof.

FIG. 6 is a left side view thereof.

FIG. 7 is a front view thereof; and,

FIG. 8 is a back view thereof.

1 Claim, 4 Drawing Sheets
